UNITED STATES PATENT OFFICE.

EDWARD A. JONES, OF PITTSFIELD, MASSACHUSETTS.

BEATING-ENGINE.

1,140,830.

Specification of Letters Patent.

Patented May 25, 1915.

Application filed December 27, 1913. Serial No. 808,953.

To all whom it may concern:

Be it known that I, EDWARD A. JONES, a citizen of the United States, residing at Pittsfield, county of Berkshire, and State of Massachusetts, have invented certain new and useful Improvements in Beating-Engines, fully described and represented in the following specification and the accompanying drawings, forming a part of the same.

10 This invention relates to improvements in apparatus used in the manufacture of paper stock and more particularly to improvements in that type of apparatus known as beating engines.

15 It is one object of the present invention to provide an improved outlet construction for emptying the vats of beating and similar engines, the outlet being of large dimensions and preferably positioned in the vat 20 between the front end of the central partition or mid-feather and the roll and extending substantially the distance between the wall of the vat and the mid-feather so as to extend across the path which the stock is 25 forced to take between these walls as it circulates to the outlet, a dam being provided in the best constructions to cause a flow into the outlet, this construction permitting the vat to be emptied at a greater speed than 30 in the constructions now employed for the purpose.

It is a further object of the invention to provide an improved valve construction for controlling the outlet whereby the valve seat 35 may be maintained free from stock at the close of the emptying operation so that the valve when closed will properly seat.

It is a further object of the invention to provide a valve for the outlet which when 40 in raised position will also act as a dam or abutment to cause the stock to pass into the outlet more readily.

With these and other objects in view, the invention consists in certain improved constructions, a detailed description of which 45 will be given in connection with the accompanying drawing, in which—

Figure 1 is a side elevation partly in section of a beating engine embodying the improvements, certain parts being broken away to show the construction; Fig. 2 is a plan view of the construction illustrated in Fig. 1; Fig. 3 is a plan view on an enlarged scale with certain parts broken away of the improved outlet construction and valve; Fig. 4 is a vertical longitudinal section taken on line 4—4 of Fig. 3; and Fig. 5 is a vertical cross section taken on line 5—5 of Fig. 4, the stock retarding means and valve being shown in this figure in normal position in full lines, 60 and in full open position in dotted lines when the emptying operation is being conducted.

Referring now to said drawing, which illustrates the preferred embodiment of the 65 invention, the invention is shown as employed in a beating engine in which provision is made for supplying water under pressure to effect a free circulation of the stock. It will be understood, however, that the 70 novel features of the invention may be employed in beating engines in which such provision is not made, and in other types of beating and similar engines for treating paper stock. The engine illustrated includes a 75 vat 1, of any suitable or desired construction, being, however, as illustrated, preferably elliptical and capacitated to hold the required amount of stock, this vat being of wood, iron, cement, or other material, as desired. Mounted in the vat 1 is a beating drum 2 mounted on a shaft 3 which is journaled in any suitable or desired manner. The beating drum 2 is provided with the usual beater knives 4 which coöperate with a 80 bed plate 5 of any suitable or desired construction positioned at the bottom of the vat to beat up the stock. At the rear, or, as shown in the drawings, the left-hand side of the drum 2, is arranged the usual back-fall 85 6 which extends from one side of the vat to a horizontal partition or mid-feather 7, this mid-feather extending centrally and longitudinally of the vat for the major portion of its length. The beating drum and back 90 fall are preferably inclosed by a cover 8 of any usual or desired construction. The lower rear or left-hand portion of the back-fall 6 is cut away to form a pressure chamber 9 which extends transversely across the 100 vat between the vat and the mid-feather, the top of this chamber being formed in any suitable manner, as by plate 10. Secured on the back-fall, so as to provide a jet opening 11 between the lower edge of the plate and the bottom of the vat, the plate 10 extends to within a suitable distance of the bottom of the vat to provide this opening. The end of the pressure chamber adjacent to the side of the vat is connected with a suitable source 110 of water supply under pressure (not shown), through a pipe, as 12, as shown in Fig. 2.

From the end of the chamber adjacent the mid-feather extends a connection 13 which passes around the rear or left-hand end of the mid-feather 7, this connection being 5 adapted to supply water from the pressure chamber 9 around the end of the mid-feather, the object of this construction being to stir up or carry along the pulp or stock which is liable to accumulate against the 10 mid-feather on its return side.

Machines constructed in accordance with the invention will embody an outlet which is of large dimensions and which will be located in the raceway formed by the mid-feather and the walls of the beater tub, this 15 outlet extending substantially, in the best constructions, across the raceway so as to lie in the path of the stock, whereby the stock as it circulates about the vat passes 20 rapidly through the outlet when the latter is opened. The outlet is further provided with an improved valve construction, and this valve will in the best form of machine act when opened as a dam or abutment and 25 cause an even more rapid delivery of the stock through the outlet. The constructions employed to effect these objects may be somewhat varied. In the particular construction illustrated, the outlet is made of 30 large dimensions, and is preferably positioned in the vat inside the end of the mid-feather between the front end of the mid-feather and the roll. To provide a large free opening, this outlet, which is marked 35 14, extends substantially between the side of the vat and the mid-feather, as illustrated. The valve for controlling the outlet may be of any suitable character and operate in any suitable manner. In the particular 40 construction illustrated, the walls of the outlet 14 form a seat for the valve 15, which is in the form of a plate extending the width of the outlet. This valve plate 15 is pivotally mounted so that it may be 45 swung upwardly to open the outlet in the direction away from the course of the stock through the vat, the valve plate thus acting as a dam or abutment for stopping the stock and directing it through the outlet. The 50 valve may be thus mounted in any suitable manner. In the particular construction illustrated, the walls of the outlet 14 are provided with enlarged portions or pockets 55 16 at suitable points, in which operate swinging arms 17 pivotally mounted on a short rock shaft 18, suitably journaled in the pocket walls and the side of the machine. These swinging arms carry the valve plate 15 before referred to, which is mounted on 60 the arms in any suitable manner. In the best construction, the plate will be mounted on the arms so as to be capable of taking a slight swiveling movement to insure its proper seating when closed. As shown, the 65 arms 17 are formed at their free end with

forks 19, into which take projections 20 on the valve plate, the projections being held in the forks of the arms by roller pins 21, which permits the plate to have a slight swiveling movement. The plate is thus 70 practically pivotally mounted in the arms, and thus is caused to properly seat when the valve is closed. The walls of the outlet 14 are provided with flanges 22, and the outlet is secured to the bottom of the vat by 75 screws 23, suitable packing 24 being interposed between the flanges and the bottom of the vat to insure a tight joint. The lower surface of the valve plate, where the same seats on the outlet, is or may be likewise 80 provided with suitable packing 25 to insure a tight joint when the valve is closed.

The rock shaft 18 is operated to swing the arms and lift the valve plate, in any suitable manner. As illustrated, there is provided a 85 hand lever 26, secured to the end of the shaft on the outside of the machine, by which the shaft may be rocked in its bearings by the operator and the plate raised and lowered. It has been found in practice 90 that the stock is very liable to accumulate on and about the valve seat during the emptying operation of the vat, and this accumulation of stock may interfere with the proper closing of the valve. In machines constructed in accordance with the invention, therefore, means are provided for preventing this 95 accumulation of stock. These means may be of various characters, but as shown the outlet is provided with channels 27 extending 100 around the valve seat, these channels having their upper walls perforated, as shown at 28, through which water or other liquid under pressure may be forced, these perforations being located adjacent the top walls of 105 the outlet on which the valve plate seats. Cleansing media, as water, may be supplied to the channels in any suitable manner. In the best constructions, this will be supplied at the time the valve is open, and the supply 110 kept up until the valve is again seated, so as to effectually prevent the accumulation of stock around the valve seat. In the particular construction illustrated, water is supplied to the channels through a pipe 29, controlled by a valve 30, the water being supplied from any suitable source, not shown. The valve 30 is operated in the construction illustrated to open and supply water when the lifting movement of the valve begins, 115 by means of a slotted link 31, operatively connected with the valve spindle, this link 31 being in turn connected with the operating lever 26, before referred to. With this construction, the valve seat is kept free from 120 accumulated stock during the entire emptying operation of the vat and until the valve is actually seated, the parts being so proportioned as to permit the supply of water until the seating of the valve. 125

While the invention has been shown and described in its preferred form, it will be understood that certain changes and variations in the particular construction may be 5 made, and that the invention is not to be restricted to the precise details shown and described, nor to the exact type of beating engine illustrated.

What is claimed is:—

- 10 1. In an apparatus of the kind described the combination with a vat, of a mid-feather in the vat, a raceway being formed between the mid-feather and the vat side, a stock discharge outlet extending substantially across the raceway between the vat side and the mid-feather so as to lie across the path of the stock, and a valve for controlling the outlet.
- 20 2. In an apparatus of the kind described the combination with a vat, of a mid-feather in the vat, a raceway being formed between the mid-feather and the vat side, a stock discharge outlet extending substantially across the raceway between the vat side and the mid-feather so as to lie across the path of the stock, and a valve plate for controlling the outlet and acting in open position as a dam or abutment.
- 30 3. In an apparatus of the kind described the combination with a vat, of a mid-feather in the vat, a raceway being formed between the mid-feather and the vat side, means for supplying water to the vat under pressure, a stock discharge outlet extending substantially across the raceway between the vat side and the mid-feather so as to lie across the path of the stock, and a valve for controlling the outlet.
- 40 4. In an apparatus of the kind described the combination with a vat, of a mid-feather in the vat, a raceway being formed between the mid-feather and the vat side, means for supplying water to the vat under pressure, a stock discharge outlet extending substantially across the raceway between the vat side and the mid-feather so as to lie across the path of the stock, and a valve plate for controlling the outlet and acting in open position as a dam or abutment.
- 50 5. In an apparatus of the kind described the combination with a vat, of a stock discharge outlet therefor, a swinging valve for controlling the outlet, means for swinging

the valve, and means operated by the valve swinging means for supplying water around the valve seat to keep the same free from the accumulation of stock during the emptying of the vat.

6. In an apparatus of the kind described the combination with a vat having a mid-feather, a stock discharge outlet extending between the vat side and mid-feather, a plate forming a valve for the outlet, said plate being arranged to be swung upwardly to the side of the outlet away from the direction of travel of the stock through the vat whereby the plate acts as an abutment and causes the stock to pass into the outlet.

7. In an apparatus of the kind described the combination with a vat having a mid-feather, a beating roller in the vat on one side of the mid-feather, an outlet located between the end of the mid-feather and the roll and extending substantially between the vat side and the mid-feather and a valve 75 plate for controlling the outlet and acting when in its raised position as a dam or abutment.

8. In an apparatus of the character described the combination with a vat, of an 80 outlet therefor, a plate for controlling the outlet, arms on which the plate is mounted, pivotal connections between the plate and the arms, and means for swinging the arms to raise and lower the plate.

9. In an apparatus of the character described the combination with a vat, of an outlet therefor, a plate for controlling the outlet, a support for the plate, pivotal connections between the plate and the support, 90 and means for operating the support to raise and lower the plate.

10. In an apparatus of the character described the combination with a vat, of an outlet therefor, a plate for controlling the 95 outlet, a support for the plate, a rock-shaft carrying the support, and means located outside the machine for rocking the shaft to raise and lower the plate.

In testimony whereof, I have hereunto set 100 my hand, in the presence of two subscribing witnesses.

EDWARD A. JONES.
